198,853

PICTURE FRAME

Harvey S. Hoshour, 931 Madison Ave.,
New York 21, N.Y.

Filed Dec. 14, 1961, Ser. No. 67,910

Term of patent 14 years

(Cl. D29—20)

FIG. 1 is a front view of the picture frame;
FIG. 2 is a side view at right angles to FIG. 1;
FIG. 3 is an enlarged fragmentary perspective view of a corner thereof; and
FIG. 4 is an enlarged sectional front perspective thereof.

I claim:

The ornamental design for a picture frame, as shown.
